(57) **CLAIM**

The ornamental design for a pet vest with collar loops, as shown and described.

DESCRIPTION

FIG. 1 is a perspective view of a pet vest with collar loops, showing my new design;

FIG. 2 is a left-side elevational view thereof;

FIG. 3 is a right-side elevational view thereof;

FIG. 4 is a rear elevational view thereof;

FIG. 5 is a front elevational view thereof;

FIG. 6 is a top plan view thereof; and,

FIG. 7 is a bottom plan view thereof.

The broken lines in FIG. 1 showing a pet depict environmental matter that forms no part of the claimed design. The remaining broken lines depict stitching, and do form part of the claimed design.

1 Claim, 4 Drawing Sheets
